UNITED STATES PATENT OFFICE.

EDWIN W. FISHBURN, OF DENVER, COLORADO.

MEANS FOR ATTACHING AIR-PUMPS TO AUTOMOBILES.

1,045,272.

Specification of Letters Patent. Patented Nov. 26, 1912.

Application filed August 22, 1911. Serial No. 645,455.

To all whom it may concern:

Be it known that I, EDWIN W. FISHBURN, a citizen of the United States, residing in the city and county of Denver and State of Colorado, have invented certain new and useful Improvements in Means for Attaching Air-Pumps to Automobiles; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in means for attaching air pumps to automobiles, whereby, by the rotation of one wheel, of the machine, the tires of the other three wheels may be inflated.

The manner of operation consists in connecting one extremity of an ordinary pump for inflating tires with the foot-board of the machine, and connecting the other extremity with one of the wheels of the vehicle beyond the center, whereby, as the wheel is rotated by the operation of the engine, the pistons, carried by the pump cylinders, will be reciprocated and air forced through a tube of the desired length, carrying a nipple at its outer extremity adapted to be connected with the valves of the tires.

In order to operate the pump for inflating three tires of the machine, it is only necessary to jack up the rear axle at one end, whereby the wheel, which is to serve as the motor, or device for directly operating the pump, is raised from the ground or other surface upon which the machine stands. Then, by starting the engine, the raised wheel may be rotated. The opposite extremities of the pump are pivotally connected with the machine, whereby, as the wheel rotates, the pump may oscillate from its pivotal connection with the foot-board of the machine.

In my improved construction, provision is made for adjustably connecting the plate at the lower extremity of the pump cylinders with the foot-board of the machine, whereby the distance between the center of the wheel, which is to operate the pump, and the point of its connection with the foot-board, may be regulated at will. This point of connection is determined by the stroke of the pump pistons. In other words, it is necessary to so regulate the connection of the pump with

the foot-board that the pistons may move practically the full length of their respective cylinders, and the farther the piston rod extremity of the pump is from the center or axis of the wheel, the farther should the opposite extremity of the pump be connected from the same center, in order that the pump may operate properly.

Another important feature of my improved construction consists in means whereby both extremities of the pump,—that is to say, the extremity carrying the plate to which the cylinders are secured,—and the handle connected with the piston rods are readily detachable from the foot-board and the wheel, respectively. This is accomplished through the instrumentality of bolts having hooks at one extremity adapted to engage the spokes of the wheel and winged nuts at their opposite extremities, whereby the bolts are readily adjustable. Similar bolts are also employed connecting the cylinder plate of the pump to the yoke, which is pivotally connected to the foot-board of the machine. Another set of similar bolts is employed in connecting the yoke with the handle of the pump, the handle engaging extremities of the bolts being curved to fit the outer extremity of the handle, whereby the handle may turn in the curved portions of the bolts whenever it may be necessary; as, for instance, when the opposite extremity of the pump changes its relative position with reference to the machine. It will be understood that, in some machines, the foot-board extends farther laterally with reference to the position of the wheel than in others; consequently, this movable connection between the handle of the pump and the bolts connecting it with the pivoted yoke is important.

In my improved construction, the pivot pin, upon which the cylinder extremity of the pump moves, is mounted on a metal strap, longitudinally adjustable on a member clamped to the foot-board. It is not always practicable to change the position of the clamp, due to the presence of the tool box or other obstruction on the foot-board. By virtue of this adjustable metal strap, the distance between the pivot at this extremity of the pump and the axis of the wheel may be regulated without changing the position of the clamp. In another form of my improved construction, the pivot pin is mounted at one extremity of the clamp. In this form of construction, by reversing the clamp, the

5 pivot pin may be thrown nearer to or farther from the axle of the operating wheel, as may be desired, while the clamp occupies the same position with its ends reversed. The 10 opposite pivot pin, or that on which the yoke attached with the handle extremity of the pump is pivoted, is mounted near the inner edge of a plate, the latter having bolts applied near its outer edge for connecting the 15 plate with the spokes of the wheel. The distance between the pivot point of the plate and the points where the bolts are connected is such that these bolts may be located outside of the band brake of the wheel, while the pivot pin is located between the band 20 wheel of the brake and the axis. By virtue of this construction and arrangement, it becomes practicable to locate the pivot pin for the handle extremity of the pump comparatively near the axle. This is important, since it is desirable to limit the length of stroke imparted by the wheel to the pistons during the pumping operation.

25 Having briefly outlined my improved construction, I will proceed to describe the same in detail, reference being made to the accompanying drawing, in which is illustrated an embodiment thereof.

30 In this drawing: Figure 1 is a fragmentary side elevation of an automobile, showing a pump connected after the manner of my invention. Fig. 2 is a view looking in the direction of arrow 2, Fig. 1, the parts being shown on a larger scale. In this view, the foot-board is indicated in dotted lines, and the clamp, mounted on the foot-board carrying the pivot pin, is shown in end elevation. Fig. 3 is a view looking in the direction of arrow 3, Fig. 3, the adjustable 35 strap connected with the clamp being broken away. Fig. 4 is a detail view of one of the securing bolts. Fig. 5 is a detail view of the foot-board clamp, showing the adjustable metal strap carrying the pivot pin in connection therewith. Fig. 6 is a view of the 40 handle extremity of the pump, shown in connection with the means for attaching the same to the wheel, the parts being shown on a larger scale than in Fig. 1. Fig. 7 is a top view of the same construction, showing the handle extremity of the pump and the yoke connected therewith. Fig. 8 is an end elevation of the handle with the attaching yoke therefor. Fig. 9 is a side view of the pump 45 and its connections, the means for attaching the same to the foot-board of the machine being different from that illustrated in the other views. Fig. 10 is a view, looking in the direction of arrow 10, Fig. 9.

50 The same reference characters indicate the same parts in all the views.

55 Referring first to Figs. 1 to 8, inclusive, let the numeral 5 designate the body of an automobile and 6 one of the rear wheels thereof. To the foot-board 7 on one side of

the machine is secured a U-shaped member 8, whose parallel flanges engage the upper and lower surfaces, respectively, of the foot-board. This member is secured to the foot-board by means of set bolts 9, threaded in 70 openings 10, formed in the lower flange of the clamping member, the screws being caused to engage the foot-board in clamping relation. To the outer surface of the clamping member 8 is adjustably secured, by 75 means of bolts 12, a metal strap 13 having a series of openings 14 adapted to register with the two openings in the clamp for the reception of the bolts 12, which are threaded into the outer portion of the clamp, after 80 passing through the strap. Upon the outer extremity of this strap is mounted a pivot pin 15 which engages an opening 16 formed in a yoke 17 attached to the base plate 18 of the pump by means of bolts 19, having parts 85 20 bent at right angles to the threaded part of the bolts and arranged to engage the base plate on its surface opposite that to which the yoke is applied. When these bolts are tightened by the use of nuts 21, the yoke is 90 properly secured to the base of the pump. In order that the yoke may be adapted for use with pumps having base plates of varying width, the opposite extremities of the yoke are provided with ears 22 having slots 95 23 of such length as to allow the bolts a considerable range of adjustment. These ears 22 project from the opposite extremities of the yoke, in opposite directions, and the bolts passed therethrough are, therefore, arranged 100 in staggered relation, whereby their bent portions 20 engage the base plate on opposite sides. By virtue of the fact that these bolts extend beyond the base plate of the pump and do not pass therethrough, it is 105 evident that the pump may be connected with the pivoted yoke, without the necessity of boring holes in the base plate thereof. This is considered an important advantage, since the attachment can be made by any 110 person, without the assistance of a mechanic.

115 The handle 4 of the pump, which is secured to the piston rod 2 in the usual manner, is connected with a yoke 26 by means of bolts 24, having curved extremities 25, which engage the opposite extremities of the handle in staggered relation, the said bolts being passed through ears 27 projecting from the extremities of the yoke in opposite directions. This connection of the yoke with 120 the handle of the pump is such that the handle may turn within the curved portions of the securing bolts, thus making it practicable to change the angle of the pump's direction, wherever it may be necessary on 125 different machines, by reason of the fact that the lateral projection of the foot-board varies on machines of different makes. This yoke 26 is pivotally connected with a plate 28, which is secured to two spokes 29 of 130

the wheel at a suitable distance beyond the axle by means of bolts 30, having hook-shaped extremities 31, which engage the spokes on one side of the plate, the bolt 5 protruding beyond the opposite side of the plate and being threaded to receive winged nuts 32, which may be applied by hand, thus making it practicable to connect the plate without employing a mechanic.

10 The pivotal connection between the plate and the yoke is formed by virtue of a pin 33, which is secured to the plate near the inner edge thereof, meaning the edge nearer the axle of the wheel. The outer extremity 15 34 of this pivot pin is reduced in size and shouldered to pass through an opening 35, formed in the yoke midway between the extremities of the latter, the yoke being prevented from slipping off the pivot pin by 20 means of a cotter pin 36, or other suitable fastening device.

By virtue of this construction and arrangement, it becomes practicable to so arrange the plate 28 that the pivot pin may 25 be between the brake drum 37 of the wheel 6 and the axle, while the bolts 30 are located outside of this drum, thus securing the advantage of locating the pivot pin as near the center of the wheel as desired. This 30 feature is illustrated in Fig. 1, in which the relative position of the plate 28 and the yoke 26, where the pump is connected with the wheel, is disclosed.

In the form of construction illustrated in 35 Figs. 9 and 10, the base plate 18 of the pump is connected with the yoke 16 in substantially the same manner as heretofore described, when referring to the other form of construction. This yoke, however, is provided with a hook 38, adapted to interlock with an eye 39 formed on the outer extremity of a pin 40, mounted on the clamp 8, being located on one extremity of the said clamp, and stationary thereon. By virtue 40 of this interlocking hook-and-eye construction, the position of the pump may vary to harmonize with differences in construction of different machines with reference to the location of the foot-board and the outer extremity of the pin 33, with which the plate 28 is equipped. It will be understood that this pin 33 must be of sufficient length to allow the piston rod 2 of the pump to pass 45 outside of the outer extremity of the wheel 55 axle, during the pumping operation. Under these circumstances, ordinarily the outer extremity of the pin 33 will project laterally beyond the outer extremity of the pin 40 mounted on the clamp 8. Hence, the 50 necessity of a sort of universal joint connection between the base plate of the pump and the pin 40, whereby movement is allowed both laterally and vertically. The 55 vertical oscillation of the pump is necessary during the rotation of the wheel 6 with

which the pump is connected. The lateral oscillation or movement is also permitted by virtue of the connection heretofore described.

It will be understood that, by reversing 70 the clamp 8, the pin 40 will be thrown nearer the axle of the wheel and into the position shown in Fig. 9. When this is done, the top and bottom flanges of the clamp 8 have changed positions. In other words, the 75 flange, which is below when the clamp is arranged as in Fig. 9, will be above the foot-board when the clamp is reversed. Hence, it will be necessary to insert the securing screws 9 in the top flange of the clamp, when 80 the latter is in the reverse position. This reversing movement of the clamp permits a variation in the distance between the center of the axle and the pin 40 by several inches, which will ordinarily be sufficient to 85 make it practicable to use a standard construction of clamp with most machines upon the market.

From the foregoing description, the use and operation of my improved construction 90 will be readily understood. In order to operate the pump by means of the wheel 6, the extremity of the axle 41, upon which the operating wheel is located, will be raised from the surface 42 upon which the machine rests, by the use of a jack 43 of ordinary construction. As soon as this is done, the pump is connected with the foot-board by attaching the clamp 8 thereto, assuming that the yoke 17 is first connected with the 95 pivot pin 15 mounted on the metal strap 13, as heretofore described, the handle or opposite extremity of the pump being connected with the spokes of the wheel 6 in suitable proximity to the axle for operating 100 purposes. The engine is then started, whereby the wheel 6 will be rotated to reciprocate the pistons in the pump cylinders 44 and 45. This pump, as illustrated in the drawing, is the ordinary hand pump and may be 105 utilized in connection with my improved attachments, without employing a mechanic to change the pump in any manner whatever. The attachments to the base plate and the handle of the pump, respectively, 110 may be readily made by any person, since no especial skill is required.

Having thus described my invention, what I claim is:

1. The combination with an automobile 120 and a pump of the class described, of means for connecting one extremity of the pump with a wheel of the vehicle, said means comprising a plate detachably applied to the spokes of the wheel in a plane at right angles to the axis of the wheel, a wrist pin mounted on the plate and extending at right angles to the plane thereof, the wrist pin being supported independently of the axle, a yoke pivotally connected with the pin, the 125 130

4
pump extremity being directly connected with the yoke, the opposite extremity of the pump being connected with the vehicle to permit vertical oscillation.

5 2. The combination with an automobile and a pump, of a plate detachably connected with the spokes of the wheel beyond the axle by means of fastening devices applied to the plate near the outer edge thereof, the 10 said plate lying in a plane at right angles to the axis of the wheel, a pin mounted on said plate near the inner edge thereof and extending parallel with the axis of the wheel, a yoke pivotally connected with the 15 pin, the opposite extremity of the pump being connected with the wheel of the vehicle to permit vertical oscillation during the pumping action, substantially as described.

3. The combination with an automobile 20 and a pump, of means for connecting the handle extremity of the pump to a wheel of the vehicle, comprising a plate detachably applied to the wheel in a plane at right angles to the axis of the wheel, a pin mounted on the said plate and extending parallel with the axis of the wheel, a yoke pivoted on the pin, hook-shaped bolts passed through openings in the yoke, the hooks of the bolts engaging the handle of the pump on opposite sides to permit the pump handle to turn in the hooks to allow the lateral movement of the pump, the opposite extremity of the pump being pivotally connected with the body of the vehicle to permit vertical oscillation, substantially as described.

4. The combination with a pump, of means for attaching the opposite extremities of the pump to the vehicle, comprising yokes secured to the respective extremities of the 40 pump by means of hook-shaped bolts passed through openings in the yokes extending beyond the parts with which the yokes are connected, the bolts being arranged in staggered relation, and means adapted to be applied 45 to the vehicle with which the yokes are pivotally connected to allow oscillation of the pump, substantially as described.

5. The combination with a pump, of a yoke applied to the handle extremity of the 50 pump by means of hook-shaped bolts passing through openings in lugs extending in opposite directions from the yoke, the hook-shaped extremities of the bolts engaging the opposite extremities of the pump handle, a 55 plate carrying a pin upon which the yoke is pivoted, means for connecting the plate with a wheel of a vehicle, the opposite extremity of the pump being equipped with a yoke connected with the pump by means of bolts 60 having parts extending substantially at right angles to each other, and a clamp adapted to be connected with the foot-board of a vehicle and carrying a pin on which the

yoke applied to the adjacent extremity of the pump is adapted to pivot, substantially as described.

6. The combination with a pump, of the class described, of a yoke connected with the handle extremity of the pump to allow the pump handle to turn in the yoke, and a plate 70 upon which the yoke is pivoted, a second yoke rigidly connected with the opposite extremity of the pump, and a clamp with which the last-named yoke is pivotally connected to permit the pump to oscillate, substantially as described.

7. The combination with a vehicle and a pump of the class described, of means for connecting one extremity of the pump to a wheel of the vehicle beyond the axle, to obtain a crank movement when the wheel rotates, the said means including a plate, and bolts passed through the plate and having hooked extremities which engage the spokes of the wheel to clamp the plate in place, the 80 pump extremity being pivotally connected with the plate to allow the pump to oscillate, the opposite extremity of the pump being pivotally connected with the framework of the vehicle, substantially as described.

8. The combination with a vehicle and a pump of the class described, of means for connecting one extremity of the pump to a wheel of the vehicle beyond the axle to obtain a crank movement when the wheel rotates, the said means including a plate and bolts passed through the plate and having hooked extremities which engage the spokes of the wheel, the said plate having a wrist pin on which the pump extremity is journaled, the wrist pin being supported independently of the axle, the adjacent extremity of the pump being journaled on the wrist pin, the opposite extremity of the pump being pivotally connected with the 105 framework of the vehicle, substantially as described.

9. The combination with a vehicle and a pump, of means for pivotally connecting one extremity of the pump with a wheel of the vehicle beyond the axle of the wheel, to give a crank movement as the wheel rotates, the said means including a plate secured to the spokes and a wrist pin mounted on the plate, the said pin and plate receiving their entire support from the spokes of the vehicle, the opposite extremity of the pump being pivotally connected with the vehicle to permit vertical oscillation of the pump, substantially as described.

In testimony whereof I affix my signature in presence of two witnesses.

EDWIN W. FISHBURN.
